CLAIM

The ornamental design for a box lid, as shown and described.

DESCRIPTION

FIG. 1 is a perspective view of a box lid;

FIG. 2 is an exploded view of the box lid of FIG. 1;

FIG. 3 is a top plan view of the box lid of FIG. 1;

FIG. 4 is a bottom plan of the box lid of FIG. 1; and,

FIG. 5 is a side elevational view of the box lid of FIG. 1. The box shown in broken lines is environmental subject matter included to illustrate how the design may appear when used on a box and forms no part of the claimed design.

1 Claim, 2 Drawing Sheets(56)
